(57) **CLAIM**

The ornamental design for a pump keg with adjustable tap dispenser as shown and described.

DESCRIPTION

FIG. 1 is a front perspective view of the pump keg with adjustable tap dispenser of the instant invention;

FIG. 2 is a left side view thereof;

FIG. 3 is a right side view thereof;

FIG. 4 is a front side view thereof;

FIG. 5 is a back side view thereof;

FIG. 6 is a top view thereof; and,

FIG. 7 is a bottom view thereof.

The broken lines represent environmental subject matter and form no part of the claimed design.
